(57) **CLAIM**

The ornamental design for a glove as shown and described.

DESCRIPTION

FIG. 1 is a top plan view of a glove;

FIG. 2 is a bottom plan view of the glove shown in FIG. 1;

FIG. 3 is a front elevational view thereof;

FIG. 4 is a rear elevational view thereof;

FIG. 5 is a right side elevational view thereof;

FIG. 6 is a left side elevational view thereof; and,

FIG. 7 is a top perspective view of the glove, depicted in a condition of use.

The broken lines in FIGS. 1-6 depict portions of the glove and form no part of the claimed design. The additional broken lines in FIG. 7, depicting parts of a hand and part of an arm, depict environmental structure and form no part of the claimed design.

1 Claim, 3 Drawing Sheets
